(57)

CLAIM

The ornamental design for a valve stem cap, as shown and described.

DESCRIPTION

FIG. 1 is a perspective of the valve stem cap;

FIG. 2 is a front view thereof;

FIG. 3 is a top view thereof;

FIG. 4 is a bottom view thereof;

FIG. 5 is a right side view thereof;

FIG. 6 is a left side view thereof;

FIG. 7 is a cross-sectional side view of the valve stem cap taken along 7-7 of FIG. 3; and,

FIG. 8 is a partially enlarged view showing the central portion of the valve stem cap taken from the encircled area in the FIG. 7 drawing view.

1 Claim, 8 Drawing Sheets
